SECTIONAL FORM FOR MAKING REINFORCED PILES

Filed Nov. 3, 1928

INVENTOR:
HOWARD H. JENKINS,

By: *John D. Ringer,
his Atty.*

UNITED STATES PATENT OFFICE

HOWARD H. JENKINS, OF LOS ANGELES, CALIFORNIA, ASSIGNOR TO AMERICAN CONCRETE PIPE COMPANY, OF LOS ANGELES, CALIFORNIA

SECTIONAL FORM FOR MAKING REINFORCED PILES

Application filed November 3, 1928. Serial No. 316,978.

This invention relates to devices in which concrete and other similar suitable material can be handled for making piles or posts of considerable length.

5 One of the objects of this invention is to provide a form in which a pile can be manufactured with a central bore or hole throughout the length of the pile without material or any particular effort or skill on the part 10 of the person handling the material in the form.

Another object is to produce a form that can be rotated at considerable speed around its longitudinal axis so that any material 15 disposed in the form will by centrifugal force be forced against the inside of the form away from the central axis so as to automatically leave a central passage throughout the length of the pile when the 20 pile is rotated with the form.

Another object is to provide a form in which reenforcing material can be held to become firmly and properly imbedded in any material disposed in the form.

25 Another object is to provide a form made in sections whereby a pile of any desired length can be manufactured.

Another object is to provide a form that can easily be removed from such a pile.

30 Another object is to provide a form that can be held together at the adjoining ends by a closed ring.

Other objects will appear from the following description and appended claims as 35 well as from the accompanying drawings, in which—

Fig. 1 is a fragmentary longitudinal mid-sectional view of a form with adjoining flanges, one closure of a somewhat pointed 40 end and another closure in form of a plain plate or flange whereby piles can be manufactured according to the principles of this invention.

Fig. 2 is a cross-section through the form 45 on line 2—2 of Fig. 1.

Fig. 3 is an end elevation of the closed interconnecting ring to be disposed between form sections.

Fig. 4 is a somewhat diagrammatic illustration in end view showing the manner in

which the form can be mounted on rollers whereby the form may be rotated around its longitudinal axis.

Fig. 5 is an end elevation of the end-closing flange seen in the direction of the arrow 55 5 indicated in Fig. 1.

As illustrated, the form consists principally of split tubular members 6 provided with connecting-flanges 7 whereby tubular members can be joined in sections endwise 60 into a desired longer form.

A typical section consists then principally of longitudinally split members 6 and a flange 7 on each of these members, as more clearly illustrated by numerals 6_a and 7_a in 65 Fig. 1. The split members are provided with longitudinally disposed flanges 8 whereby the members can be longitudinally fastened together into a rigid section.

It is immaterial whether the cross-section 70 of such a section is then exactly of a round or circular shape or any other shape. Columns of hexagonal shape may be desired and the form can easily be arranged so that such a result can be accomplished in the 75 form, and it will be understood that any other outside form can be provided for by the shape of the form.

The principal feature of this invention is that the form is provided with end-flanges 80 that can be disposed on rollers whereby the form can be rotated around its longitudinal axis regardless of the outer shape wherefore the flanges, of course, must be of circular outside to allow such a mounting 85 for rotation of the form on the end-flanges in the manner indicated in Fig. 4.

As illustrated in Fig. 2, for a round column or pile the members 6 are preferably 90 in halves with the longitudinal edges 9 and 9_a either set back or protruding beyond the flange 8 on the members, whereby an aligning of the halves into a firmly interconnected hole is facilitated.

The longitudinal flanges are provided 95 with a number of holes or apertures 10 for bolts not shown in the drawings, whereby these flanges can be connected to hold the halves of this tubular section together. The end-flanges, on the other hand, are also pro- 100

vided with holes to receive the bolts 11, whereby several form sections can be connected endwise.

The interconnecting flange 12 is provided with holes 13 to align with the holes in the end-flanges 7 whereby the bolts 11 can be pressed through the flanges 7 and through the interconnecting flange 12. This interconnecting flange is, furthermore, provided with annular beads 14 to fit into grooves 15 in the end-flanges 7, facilitating an aligning and assuring a firm interconnecting of the form sections.

A conical closure 16 is provided to be secured to one end of one of the form sections whereby any material disposed in this form may receive a pointed end which facilitates a driving of a finished concrete post into the ground.

A plain end-plate 17 is provided to be secured on the end of one of the form sections, serving to hold concrete and similar material in the form in a certain required manner. This end-flange is provided with a central aperture 18 closed by a removable plate 19. The end-plate 17 is, furthermore, provided with holes 20 to facilitate a passing of reenforcing bars through this end-plate.

With this arrangement short ends of piles can be manufactured. The plain end-plate 17 can be attached to both ends of form sections and reenforcing bars can be disposed in the forms so as to protrude to a suitable extent through the plain end-plate 17 while post material is disposed in the form, so that such a short pile section when finished has reenforcing bars protruding from its end which serve to interconnect several short pile sections by placing concrete between the ends of such short pile sections around the protruding reenforcing bar-ends.

To produce a concrete pile with the reenforcing material properly disposed through and imbedded in the material of the pile and with a central hole throughout its length, in case of making short pile sections, the suitable length of form sections is closed by the end-plates 17 on both ends with one closing plate 19, or the closing plate 19 on each of the end-plates, removed while concrete or other suitable pile material is deposited in the form and while the form with the pile material is rotated on a suitable rotating and supporting machine, so that, while the form is so rotated, any surplus pile material and any surplus water can run out or discharge out of the holes 18 in the end-plates 17, whereby a passage is produced throughout the length of the pile material so rotated in the form.

It will be understood that with the form disclosed herewith one pile section can be produced with a pointed end by means of the pointed closure 16 of the form and other pile sections can be produced with the reen-

forcing bars protruding from their ends, and that several of such pile sections can be interconnected with one pointed pile section into one long pile of any desired or required length.

The end-flanges 7 are, furthermore, provided with overlapping or engaging edges 21 and 21_a whereby interconnected form sections can be sealed at the joints, so that a finished pile can be produced with an evenly smooth outside.

Having thus described my invention, I claim:

1. A longitudinally and transversely sectioned pile form embodying flanges with cylindrical periphery portions whereby the sectioned form when connected and supported on a suitable machinery can be rotated, the flanges having shoulder portions for holding the form against endwise movements while rolling on the machinery, and an end-flange having an opening whereby surplus pile material and surplus water can be discharged through such opening while the form is being rotated.

2. In a pile form, longitudinally split members, engaging means along the longitudinal edges of the members for interconnecting the members into a closed longitudinal form section, end-flanges on the opposite ends of the section embodying aligning edges whereby several sections can be aligned into a uniformly hollow form, a ring between each of the sections having a cylindrical periphery whereby the form can be supported on a suitable machinery for rotating the form around its longitudinal axis, and closing members for the opposite ends of the interconnected sections.

In testimony that I claim the foregoing as my invention I have signed my name.

HOWARD H. JENKINS.
